UNITED STATES PATENT OFFICE.

WINFIELD SCOTT BRINK, OF AKRON, OHIO, ASSIGNOR TO THE FIRESTONE STEEL PRODUCTS COMPANY, OF AKRON, OHIO, A CORPORATION OF OHIO.

RIM-FEEDING DEVICE.

Application filed November 6, 1926. Serial No. 146,597.

The general purpose of the invention is to provide apparatus for delivering annular objects into engagement with the moving parts of a machine to have an operation of 5 any character performed thereon, and then for removing said objects from the machine, all within the control of an operator, but without the dangerous manual handling here- 10 fore practiced. For purposes of illustration, the feeding device will be described as used in connection with a machine for rolling rims for pneumatic automobile tires, the rim being fed into the roller in an approximately annular flat band form and being removed 15 after it is rolled to true annular form and with the desired side flanges.

One object is to provide means for feeding blank rims into a roller and simultaneously removing a rolled rim from said rollers. Another object is to provide means for feeding a blank rim between a pair of rollers and for simultaneously urging said rollers together to roll said rim to any desired 20 contour. Another object is to provide fluid- 25 operated means for feeding rims into rolling machines and removing the same therefrom. A further object is to provide a feeder arm to support rims which are somewhat eccentric or out of round.

The foregoing and other objects are obtained by the apparatus illustrated in the accompanying drawings and described below. It is to be understood that the invention is not limited to use with the particular machine described nor limited to the 35 specific form thereof shown and described.

Of the accompanying drawings: Figure 1 is a front elevation of a device embodying the invention illustrating the 40 same in position to remove a rim from a rolling machine;

Figure 2 is a plan thereof showing only the lower roll of the rolling machine; and

Figure 3 is a plan view of the device in 45 its position after a rim is removed from the rolls and another one fed therebetween, a part of the device being broken away.

Referring more particularly to the drawings, 50 10 represents the frame of a rolling machine, as an example of a suitable machine in connection with which the inven-

tion may be used, and 11 and 12 are the rolls thereof. A blank rim 13 to be rolled is represented by a dotted line and is shown supported by a feeder arm 14, while a finished rim 13 is shown supported by a removing arm 15. Arms 14 and 15 are attached to vertical shafts 16 and 17, respectively, which are journaled in brackets 18, 18 and 19, 19 mounted on frame 10, the arms being thus mounted to swing toward and from the roll 12. A pair of journals 20, 20 and 21, 21 are adjustably mounted along arms 14 and 15 and have pivoted thereon at 22, 22 and 23, 23 brackets 24, 24 and 25, 25. The upper and lower ends of each bracket have mounted at right angles thereto a finger 26, the fingers on arm 14 being adapted to carry a rim and place it upon roll 12 when arm 14 is swung toward said roll and the fingers on arm 15 being adapted to engage the rim and remove it from said roll when arm 15 is swung away therefrom. Suitable mechanism is provided for limiting the pivotal movement of brackets 24, 24 and 25, 25, the form illustrated 70 comprising a pair of spaced lugs 27, 27 on each of journals 20, 20 and 21, 21 and an intermediate lug 28 on the bracket, said intermediate lug being resiliently centered between said spaced lugs by springs 29, 29 carried by a pin 30 mounted on said spaced lugs, said pin passing through an enlarged hole or slot in said intermediate lug.

Movement of the swinging arms 14 and 15 is maintained in a definite angular relation 85 by means of a chain 31 passing around sprockets 32 and 33 mounted on shafts 16 and 17 respectively, said chain being tightened by a suitable idler 34. If desired, arm 14 may be made to swing through a lesser angle than arm 15 by making sprocket 32 larger than sprocket 33 as illustrated. Arm 14 will thus swing from its position in Figure 2 to its position in Figure 3 while arm 15 is swinging through a half circle, in which former position of the arm 14, the rim 13 may more readily be placed on the arm by the operative and need travel but a short distance before engaging the rolls.

The arms may be operated by manually 100 swinging arm 14, but are preferably actuated by a double-acting air cylinder 35

mounted on a suitable base 36 and controlled by a four-way valve 37. Piston 38, recipro-
cable in cylinder 35, is connected by piston
rod 39 to a gear rack 40, which rotates shaft
5 16 by meshing with a pinion 41 keyed thereon.

In order to operate the rolls 11 and 12 to
urge them together in timed relation to the
feeding of the rims, a valve 42, connected to a
10 hydraulic roll-raising cylinder (not shown),
is mounted on base 36 and is actuated by
piston rod 39.

A standard 43 is attached to the floor as
shown in Figure 3 and has an overhanging
end 44 adapted to engage the top of rim 13 to
15 eject the same from arm 15 as the latter com-
pletes its outward swing.

In the operation of the apparatus, the op-
erative places a blank rim on the fingers 26
of arm 14 and opens valve 37 to admit air
20 pressure to the right end of cylinder 35 to
move piston rod 39 to the left, swing arm 14
inwardly and deliver the rim between the
rolls of the rolling machine, while arm 15 is
25 swung outwardly to remove a previously
rolled rim. At the same time, valve 42 is
also actuated by piston rod 39 to admit
water pressure to the hydraulic cylinder to
raise lower roll 12 and force it against the
rim and the rim against upper roll 11. When
30 the rolling operation is finished, the operative
throws the valve 37 over, whereupon air cyl-
inder operates to withdraw arm 14 and swing
arm 15 inwardly to receive the finished rim.
At the same time valve 42 is shifted to reverse
35 the hydraulic cylinder and lower the roll 12
thereby depositing the finished rim on arm
15. As arm 14 delivers a new rim to the
rolls, arm 15 with the finished rim swings
outwardly through a half-circle until end 44
40 of standard 43 ejects the rim, which then
drops into a suitable conveyor chute to pass
on to the next operation.

As the blank rims are generally eccentric
or flat-sided due to preliminary rough rolling
45 and welding, they have considerable side
sway when first placed in the rolls. In
order that the supporting means may sway
with the rim without bending the rim or
breaking the supporting arms, brackets 24,
50 24 are pivoted and are resiliently held in
position by springs 29. Brackets 25, 25 may
be likewise pivoted to have a yielding grip-
ping action on the finished rim. On opera-
tions performed on the rim after it has been
55 rolled to true annular form, the pivoted
brackets may be dispensed with and other
means used to support the rim as will be
understood.

A simple and effective means is thus pro-
60 vided for feeding annular objects into ma-
chinery and removing the same therefrom
after an operation has been performed there-
on. Dangerous manual operations are there-
by eliminated and, due to the device being

practically automatic, it eliminates consid- 65
erable labor and time in the many manufac-
turing operations in which it may be utilized.

Modifications of the above described in-
vention may be resorted to without departing
from the spirit thereof or the scope of the 70
 appended claims.

What is claimed is:

1. In combination with a machine having
relatively movable rolls, a supporting arm at-
tached to a vertical shaft mounted on said ma- 75
chine, said shaft being journaled to swing
said arm into and out of alignment with said
rolls to deliver a blank rim therebetween, a
second supporting arm attached to a vertical
shaft, said shaft being journaled to swing
80 said second arm out of and into alignment
with said rolls, successively and alternately
with said first arm, to remove a rolled rim
from said rolls, a large sprocket keyed to said
first-mentioned shaft, a smaller sprocket 85
keyed to said last-mentioned shaft, a chain
connecting said sprockets, whereby said arms
may be swung in definite angular relation to
each other and the delivering arm swung
through a lesser angle than said removing
90 arm, means for swinging said arms, comprising
a double-acting air cylinder having at-
tached to the piston rod thereof a gear rack
meshing with a pinion keyed to said first-
named shaft, a valve shiftable by said piston
95 rod for controlling the relative movement of
said rolls in timed relation to the rim-deliver-
ing operation, a manually operable valve for
controlling said air cylinder, and a standard
for ejecting a rolled rim from the second sup- 100
porting arm as the latter is swung away from
said rolls.

2. In combination with a machine adapted
to perform an operation on annular objects,
means for delivering said objects to said ma- 105
chine and for removing the same therefrom,
comprising a pair of oscillatory object sup-
porting arms adapted alternately to be swung
into engagement with said machine, means
for swinging said arms comprising a fluid-
operated cylinder, a rack and pinion connect- 110
ing said cylinder and one of said arms and a
chain engaging sprockets on the two arms,
means for controlling the operation of the
machine in timed relation with the delivering
115 of said objects, comprising a valve actuated
by said cylinder, and means for ejecting an
object from the arm removing said object
from the machine.

3. A feeder arm for delivering annular ob-
jects to a machine, said arm comprising an
oscillatory member, journal members adjust-
ably mounted thereon, a bracket pivoted on
each journal member, and means for resil-
iently limiting the pivotal movement of said
120 bracket, whereby the brackets may yieldingly
grip objects which are somewhat eccentric.

4. The combination with a machine having

5 relatively movable elements, of a feeder arm pivoted to one side of said machine for delivering work into operative engagement with one of said elements, a carrier arm pivoted to the other side of said machine for removing finished work therefrom, means for simultaneously swinging said feeder arm into

and said carrier arm out of cooperative relation with said element, and means for controlling the operation of said machine on said 10 work in timed relation to the work delivering operation.

WINFIELD SCOTT BRINK.
